UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING APPARATUS.

Original application filed January 8, 1923, Serial No. 611,275. Patent No. 1,682,749, dated September 4, 1928. Divided and this application filed January 12, 1928. Serial No. 246,179.

My invention relates to railway signaling apparatus.

I will describe one form of apparatus embodying my invention, and will then point 5 out the novel features thereof in claims.

The present application is a division of my copending application Serial No. 611,275, filed on the 8th day of January, 1923, which has matured into Patent No. 1,682,749, Sept. 10, 1928, for railway signaling apparatus.

In the accompanying drawings, Fig. 1 is a view showing in vertical section one form of relay embodying my invention, and Fig. 2 is a top plan view, with top plate removed, 15 of the relay shown in Fig. 1. Fig. 3 is a view showing a detail of the relay shown in Figs. 1 and 2. Fig. 4 is a perspective view of the magnetic core and the windings thereon of the relay shown in Figs. 1 and 2. Fig. 4^a is a 20 top plan view of a portion of the magnetic core and windings shown in Fig. 4. Figs. 5 and 6 are views showing modifications of the 25 relay shown in Figs. 1 and 2. Fig. 7 is a diagrammatic view showing one form of railway signaling system embodying the relay shown in Figs. 5 or 6.

Similar reference characters refer to similar parts in each of the several views.

Referring first to Figs. 1, 2, 3, 4 and 4^a, the 30 relay, which is designated as a whole by the reference character R, comprises a base plate 69 and a top plate 70 spaced apart by glass sides 71. Mounted on suitable supports on the base plate 69 is a substantially U-shaped 35 core 72 of magnetizable material, such as soft iron, having confronting pole-pieces 72^a and 72^b with an air gap 73 between them. This core is provided with a winding comprising two coils 3, 3 surrounding the two pole-pieces, respectively, and usually connected in 40 series when the relay is in use, and this winding I will term the "track" winding of the relay. It will be noted that when alternating current is supplied to this winding an 45 alternating flux is created in the core 72 which at any given instant flows in the same direction across all parts of the air gap 73. The core is also provided with a second winding having two sections 3^a, 3^b, each comprising 50 a plurality of superposed bars of copper or other similar material. These two sections 3^a, 3^b are mounted on the core on oppo-

site sides of the air gap and are usually connected in series when the relay is in service, each section being substantially S-shaped as 55 best shown in Figs. 1 and 4. The upper bar of the S rests against one vertical side of the core, the lower bar rests against the other vertical side of the core, and the middle bar of the S passes vertically through the middle 60 of the core. The two sections 3^a, 3^b are reversed in relative positions as best shown in Fig. 4. When alternating current is supplied to winding 3^a, which I will term the "local" winding of the relay, it will be clear 65 that at any given instant magnetic flux will flow across air gap 73 in one direction between the right-hand sections of pole-pieces 72^a and 72^b, and in the other direction between the left-hand sections of these pole 70 faces. The result of this is that when alternating currents of the same frequency but displaced in phase are supplied to windings 3 and 3^a, a shifting magnetic flux will pass through air gap 73, and the direction of 75 travel of this flux will be reversed when the polarity of the current in one winding is reversed with respect to the polarity of the current in the other.

A shaft 2^a is mounted to oscillate in suitable bearings carried by posts 67 which project upwardly from the base plate 69, and fixed to this shaft is an operating member 2 of non-magnetic electro-conductive material such as aluminum in the form of a vane or 80 disk. This member passes through the air gap 73 in core 72, and so is subjected to the shifting magnetic field created by alternating currents in the windings on this core. It follows, of course, that when both windings 3 and 3^a are energized, an electro-magnetic torque will be exerted on member 2 in 85 one direction or the other depending on the relative polarity of the currents in these windings. 90

It will be observed that with this arrangement the number of turns in the S-shaped winding 3^a is very small compared with the number of turns in winding 3. If, therefore, the two windings are to produce a comparable 100 number of ampere turns, the current through winding 3^a must be correspondingly great. In practice the current actually required in this winding is of the magnitude of several 95

hundred amperes. As shown in the drawing the immediate source of this current is the secondary winding of a special transformer Q which is placed as close as possible to the winding 3^a in order to reduce losses in connections and in this instance is mounted within the relay case 69. The secondary of this transformer comprises a single turn and the primary winding is supplied with alternating signaling current by any suitable means.

Located above the vane 2 are two contact carrying rocker arms 4 and 5, pivotally mounted in brackets suspended from the top plate 70 of the relay. Attached to rocker arm 4 is a horizontal bar 6 the free end of which is pivotally connected with a vertically disposed link 9. Similarly, attached to rocker arm 5 is a horizontal bar 7 the free end of which is pivotally attached to link 8. The lower ends of the links 8 and 9 are provided with slots 12 and 13, respectively, (see Fig. 3) and projecting into these slots are two pins 14 and 15 respectively, which pins are movable with the member 2 and are located on opposite sides of the axis of the member. As here shown, these pins pass through a slotted block 74 which is attached to the member 2 and the shaft 2^a.

30. Rocker arm 4 controls a set of contacts of which only two are shown in the drawing. One of these contacts comprises a spring 18 attached to the rocker arm 4 and co-operating with a fixed contact block 32, and this I will call the normal contact. The other contact comprises a spring 17 attached to the rocker arm and co-operating with a fixed contact block 33; this I will term one of the middle or back contacts. The rocker arm 5 likewise controls a set of contacts of which only two are shown in the drawing. These contacts comprise a spring 19 attached to the rocker arm and co-operating with a fixed contact block 20 or a fixed block 21 depending upon the position of the rocker arm. Contact 19-21 I will term a reverse contact, and contact 19-20 I will term one of the middle or back contacts of the relay. It is understood that each rocker arm may be provided with a plurality of contacts similar to those shown in Fig. 1, and in Fig. 7 where a plurality of such contacts are shown, the exponents a , b and c are used to designate the several contacts of each set.

55. The two rocker arms 4 and 5 are provided with counterweights 10 and 11 respectively which bias these arms to such positions that the middle or back contacts 17-33 and 19-20 are closed.

60. Each rocker arm 4 and 5 also carries a bar 80 which co-acts with adjustable front and back stop screws in a fixed block 81, whereby the swinging motion of the arm is restricted to the desired limits.

65. The operation of the relay shown in Fig.

1 is as follows: When one or both of the stator windings 3, 3^a are de-energized, there is, of course, no electro-magnetic torque on the movable member 2, and this member is then held in the position in which it is shown by the action of the counterweights 10 and 11 on the rocker arms 4 and 5. The back contacts 17-33 and 19-20 are then closed, whereas both the normal and reverse contacts are open. I will now assume that both stator windings 3 and 3^a become energized by currents of such relative polarity that a torque is exerted on member 2 in clockwise direction as viewed in Fig. 1. When the member moves in that direction pin 15 drives link 9 downwardly, whereas pin 14 moves freely upwardly in the slot 12 in link 8. The downward movement of link 9 causes the counterweight 11 to rise and also swings the rocker arm 4 in clockwise direction, thereby opening the back contact 17-33 and closing the normal contact 18-32. The member 2 continues its movement until the force exerted by the normal contact plus the torque due to counterweight 10 is equal to the electromagnetic torque exerted on the member. It will be observed that during such operation of the member 2 the contacts controlled by the rocker arm 5 are not affected. As soon as one or both of the stator windings become de-energized, the member 2 will be restored to its biased or initial position by the action of counterweight 10.

I will now assume that the relative polarities of the currents of the stator windings 3 and 3^a are such as to swing member 2 in counter-clockwise direction. Pin 14 then drives link 8 downwardly whereas pin 15 moves freely upwardly in the slot 13. The downward movement of link 8 raises counterweight 11 from its stop and swings the rocker arm 5 in counter-clockwise direction, thereby opening the back contact 19-20 and closing the reverse contact 19-21. During this operation of the member 2 the contacts controlled by rocker arm 4 are not affected. When torque is removed from the member 2, this member is restored to its biased position by the action of the counterweight 11.

Referring now to Fig. 5, the relay shown herein is the same as that shown in Figs. 1 to 4, with the addition of an auxiliary contact 23-24 comprising a fixed contact member 24 and a contact spring 23 mounted on insulating studs 22^b fixed to a member 22. Member 22 is attached to an arm 29 which is pivotally mounted at point 22^a, and also attached to the arm 29 is a bar 25 carrying a spring 26 the free end of which is provided with a roller 27. Roller 27 co-operates with a cam 28 fixed to the shaft on which the movable member 2 is mounted. Arm 29 carries two weights 29^a, 29^b, so that this arm together with the weights constitutes an inertia device for causing retarded operation of

contact 23-24. When the movable member 2 is in its biased or middle position, the roller 27 is raised by the cam 28 and under this condition the auxiliary contact 23-24 is closed.

5 When the movable member 2 is swung in either direction from its biased position, roller 27 is released by the cam 28, whereupon the auxiliary contact swings to the open position due to the weight of bar 25. I will now assume that the member 2 makes a continuous movement from one extreme position to the other. During such movement the roller 27 is raised momentarily by the cam 28, but owing to the effect of the inertia 10 device 29-29^a the auxiliary contact 23-24 does not close, so that the only effect of raising the roller 27 is to bend the spring 26. It will be seen, therefore, that when member 2 is in its biased position contact 23-24 is closed, when the member 2 moves to either extreme position this contact opens, and this contact does not close during continuous movement of the member 2 from either extreme position to the other.

25 It will be observed that when the member 2 swings in either direction from its biased position, the only force tending to oppose movement of the member is the force exerted by counterweight 10 or 11, and so it follows 30 that the relay requires no more operating energy than if the auxiliary contact 23-24 were not provided.

Referring now to Fig. 6, the relay shown in this view is the same as that shown in Fig. 5 except for a modified structure for controlling the auxiliary contact 23-24. In Fig. 6 the movable spring member 23 of this contact is attached to an arm 22 which in turn is fixed to a Z-shaped armature 83 operating 40 in a magnetizable core 82. The core 82 is provided with a winding 84 which is included in a circuit with a suitable source of current the terminals of which are designated B and O in the drawing. This circuit is controlled by a contact 85 governed by the cam 28 and roller 27 in such manner that the contact is open when the member 2 is in its middle or biased position, and closed when this member swings to either extreme position.

The Z-armature 83 and arm 22 are biased to such position that contact 23-24 is closed, but when winding 84 is energized the armature 83 swings to such position that this contact is open. Owing to the sluggish action of armature 83, however, the operation is such that when contact 85 opens momentarily during a continuous movement of member 2 from either extreme position to the other, a 55 complete movement of armature 83 will not occur and so contact 23-24 will not close.

60 It should be pointed out that the relay shown in Fig. 6 requires no more operating energy from the track circuit than if contact 65 23-24 were not provided. A certain amount

of additional energy is, of course, required for the operation of the Z-armature, but this energy may be supplied from a local source and does not increase the power drawn from the track circuit.

Referring now to Fig. 7, the reference characters 30 and 30^a designate the track rails of a railway along which traffic normally moves in the direction indicated by the arrow. These rails are divided by insulated joints 31 to provide a plurality of track sections, of which only two complete sections A-B and B-C are shown in the drawing. Located adjacent the entrance end of each section is a signal designated by the reference character S with an exponent corresponding to the location, each of which signals in the form here shown is of the light type comprising three lamps G, Y and R, indicating respectively when illuminated "proceed", "caution" and "stop." Each signal is controlled by a relay designated by the reference character R with an exponent corresponding to the location, each of which relays is similar to those shown in either Fig. 5 or Fig. 6. The stator winding 3 is connected directly with the track rails of the associated section, whereas the stator winding 3^a is supplied with alternating current from a transmission line 34 through the medium of transformers T and Q. Alternating signaling current is constantly supplied to the transmission line 34 by a generator 35. Suitable means are provided for displacing the phase of the current in stator winding 3 from that of the current in that of stator winding 3^a, this means as here shown being a reactance 68 interposed between the track rails and the secondary winding of each track transformer U.

As shown in Fig. 7, the section immediately to the left of point A is occupied by a car or train which is represented by an axle and pair of wheels W, so that relay R^A is de-energized. The stop lamp R of signal S^A is therefore lighted by virtue of a circuit which passes from the secondary of transformer T^A, through wires 36 and 37, auxiliary contact 24-23 of relay R^A, wire 38, contact 17^b-33^b, wire 48, contact 20^c-19^c, wire 49, lamp R of signal S^A, and wires 50, 51, 52, 53 and 47 to the secondary of transformer T^A.

Current is also supplied to the primary of a transformer U^A, the secondary of which is connected across the rails of section A-B. The circuit for the primary of this transformer is from the secondary of transformer T^A, through wires 36 and 37, auxiliary contact 24-23, wires 38 and 39, contact 17^a-33^a, wire 40, contact 20^a-19^a, wire 41, primary of transformer U^A, wire 42, contact 19-20, wire 43, contact 33-17, and wires 44, 45, 46 and 47 to the secondary of transformer T^A. The current which is thus supplied to the rails of section A-B is of what I will term reverse

relative polarity, and the result of this polarity is that the member 2 of relay R^a is swung in counter-clockwise direction, so that the reverse contacts of this relay are closed. The 5 caution lamp Y of signal S^b is lighted by virtue of a circuit which passes from the secondary of transformer T^b , through wires 36, 54, 55 and 56, contact 19^b—21^b, wire 57, lamp Y, and wires 51, 52, 53 and 47 to the secondary 10 of transformer T^b . The circuit for the primary of transformer U^b which supplies current to the track rails of section B—C passes from the secondary of transformer T^b , through wires 36, 54, 58, 59 and 60, contact 15 21—19, wire 42, primary of transformer U^b , wire 41, contact 19^a—21^a, and wires 61, 45, 46 and 47 to the secondary of transformer T^b . The polarity of this current in winding 3 of relay R^c with respect to the current in winding 3^a is opposite to the polarity of the current in winding 3 of relay R^b with respect to the current in winding 3^a, and so the current supplied to winding 3 of relay R^c is what I 20 will term of normal relative polarity. The 25 result of this polarity is that the member 2 of relay R^c is turned in clockwise direction, so that the normal contacts of this relay are closed and the reverse contacts are open. The proceed lamp G of signal S^c is lighted 30 by virtue of a circuit which passes from the secondary of transformer T^c , through wires 36, 54 and 55, contact 32^b—18^b, wire 63, lamp G and wires 52, 53 and 47 to the secondary of transformer T^c . Current of normal relative 35 polarity is supplied to the primary of transformer U^c , through a circuit which passes from the secondary of transformer T^c , through wires 36, 54, 58 and 59, contact 32—18, wires 64 and 42, primary of transformer U^c , wires 41 and 65, contact 18^a—32^a, and wires 66, 46 and 47 to the secondary of 40 transformer T^c .

When the car or train W passes out of the section in which it is shown in the drawing, relay R^a will become energized in reverse direction, so that the relative polarity of the current supplied to the rails of section A—B will be reversed. The result of this is that member 2 of relay R^a will swing from its extreme reverse position to its extreme normal position, so that momentarily the middle or back contacts 19—20 of this relay will close. The auxiliary contact 23—24 remains open, however, so that during the brief interval in 55 which the contacts 19—20 are closed current of reverse relative polarity will not be supplied to the rails of section B—C and the circuit for the stop lamp R of signal S^b will not be closed. The reason for this, of course, is that the auxiliary contact 23—24 is included in the circuit which supplies current of reverse relative polarity to the primary of transformer U^b , and this same contact is also included in the circuit for the stop lamp R. 60 It follows that during reversal of relay R^a

there will be no momentary flash of stop lamp R in signal S^b , and there will be no tendency for relay R^c to operate.

It will be observed that in Fig. 7 only one relay is used for each track section and that this one relay performs the two functions of controlling the associated signal and also controlling the relative polarity of the current supplied to the rails of the track section next in the rear. I am enabled to do this because of the fact that, as pointed out hereinbefore, each relay R requires no more operating energy from the track circuit than an ordinary 2-phase track relay, even though the auxiliary contact 23—24 is provided. 75

Although I have herein shown and described only one form of apparatus embodying my invention, it is understood that various changes and modifications may be made therein within the scope of the appended 85 claims without departing from the spirit and scope of my invention.

Having thus described my invention, what I claim is:

1. In combination, a plurality of successive 90 sections of railway track, a relay for each section having a winding connected with the rails of the section and having a movable member responding to reversals of relative polarity of the current in the rails by moving 95 to two extreme positions in opposite directions from a biased position, means controlled by said member when in either extreme position for supplying current of one relative polarity to the rails of the section in the rear 100 and when in its biased position for supplying current of the opposite relative polarity to the rails of the section in the rear, a signal for each section, means controlled by the movable member of each relay for causing the associated signal to indicate proceed or caution or stop according as said member is in one extreme position or the other extreme position or the biased position, an auxiliary contact 110 for each relay arranged when open to prevent the supply of current of said opposite relative polarity to the rails of the section in the rear and also to prevent the associated signal from indicating stop when said movable member of the relay is in the biased position, 115 said auxiliary contact being open when said member is in either extreme position and closed when said member is at rest in its biased position, and means associated with said auxiliary contact for preventing momentary closure thereof during continuous movement of said member from one extreme position to the other.

2. In combination, a plurality of successive 125 sections of railway track, a relay for each section having a winding connected with the rails of the section and having a movable member responding to reversals of relative polarity of the current in the rails by moving 130 to two extreme positions in opposite direc-

- tions from a biased position, means controlled by said member when in either extreme position for supplying current of one relative polarity to the rails of the section in the rear and when in its biased position for supplying current of the opposite relative polarity to the rails of the section in the rear, an auxiliary contact for each relay arranged when open to prevent the supply of current of said opposite relative polarity to the rails of the section in the rear when said member is in its biased position, said auxiliary contact being open when said member is in either extreme position and closed when said member occupies its biased position, and means associated with said auxiliary contact for preventing momentary closure thereof during the movement of said member from one extreme position to the other.
- 10 3. In combination, a plurality of successive sections of railway track, a relay for each section having a winding connected with the rails of the section and having a movable member responding to reversals of relative polarity of the current in the rails by moving to two extreme positions in opposite directions from a biased position, means controlled by said member when in either extreme position for supplying current of one relative polarity to the rails of the section in the rear and when in its biased position for supplying current of the opposite relative polarity to the rails of the section in the rear, a signal for each section, means controlled by the movable member of each relay for causing the associated signal to indicate proceed or caution or stop according as said member is in one extreme position or the other extreme position or the biased position, an auxiliary contact for each relay arranged when open to prevent the supply of current of said opposite relative polarity to the rails of the section in the rear and also to prevent the associated signal from indicating stop when said movable member of the relay is in the biased position, said auxiliary contact being biased to the closed position, a slow-acting electric motor for opening said auxiliary contact, and means for energizing said motor when said member occupies either extreme position.
- 20 4. In combination, a plurality of successive sections of railway track, a relay for each section having a winding connected with the rails of the section and having a movable member responding to reversals of relative polarity of the current in the rails by moving to two extreme positions in opposite directions from a biased position, means controlled by said member when in either extreme position for supplying current of one relative polarity to the rails of the section in the rear and when in its biased position for supplying current of the opposite relative polarity to the rails of the section in the rear, an auxiliary contact for each relay arranged when open to prevent the supply of current of said opposite relative polarity to the rails of the section in the rear when said member is in its biased position, said auxiliary contact being open when said member is in either extreme position and closed when said member occupies its biased position, and means associated with said auxiliary contact for preventing momentary closure thereof during the movement of said member from one extreme position to the other.
- 25 5. In combination, a plurality of successive sections of railway track, a relay for each section having a winding connected with the rails of the section and a movable member responding to reversals of relative polarity of the current in the rails by moving to two extreme positions in opposite directions from a biased position, means controlled by said member of each relay for reversing the relative polarity of the current supplied to the rails of the section in the rear, a signal for each section, means controlled by the movable member of each relay for causing the associated signal to indicate proceed or caution or stop according as said member is in one extreme position or the other extreme position or the biased position, an auxiliary contact for each relay operating when open to prevent the associated signal from indicating stop, said auxiliary contact being biased to the closed position, a slow-acting electric motor for opening said auxiliary contact, and means for energizing said motor when said member occupies either extreme position.
- 30 6. In combination, a relay having a movable member biased to a middle position and movable in opposite directions therefrom to two extreme positions, a signal, means controlled by the movable member of said relay for causing said signal to indicate proceed or caution or stop according as said member is in one extreme position or the other extreme position or the biased position, an auxiliary contact for each relay operating when open to prevent said signal from indicating stop, said auxiliary contact being biased to the closed position, a slow-acting electric motor for opening said auxiliary contact, and means for energizing said motor when said member occupies either extreme position.
- 35 7. In combination, a plurality of successive sections of railway track, a relay for each section having a winding connected with the rails of the section and a movable member responding to reversals of relative polarity of the current in the rails by moving to two extreme positions in opposite directions from a biased position, a circuit including contacts of each relay closed when the movable member is in either extreme position for supplying current of one relative polarity to the rails of the section in the rear, a second circuit including contacts of each relay closed when the movable member is in its biased position for supplying current of the opposite relative polarity to the rails of the section in the rear, an auxiliary contact for each relay arranged

relative polarity to the rails of the section in the rear, a signal for each section, a proceed indication circuit for each signal including a contact of the associated relay closed when the relay is energized in one direction, a caution indication circuit for each signal including a contact of the associated relay closed when the relay is energized in the opposite direction, a stop indication circuit for each signal including a contact of the associated relay closed when the relay is de-energized, an auxiliary contact in each relay included in the second circuit for supplying current to the rails of the section in the rear 10 and also included in the stop indication circuit for the associated signal, said auxiliary contact being open when said member is in either extreme position and closed when said member is at rest in its biased position, and 15 means associated with each auxiliary contact for preventing momentary closure thereof during continuous movement of said member from one extreme position to the other. 20 8. In combination, a plurality of successive sections of railway track, a relay for each section having a winding connected with the rails of the section and a movable member responding to reversals of relative polarity of the current in the rails by moving to two extreme 25 positions in opposite directions from a biased position, a circuit including contacts of each relay closed when the movable member is in either extreme position for supplying current of one relative polarity to the rails of the section in the rear, a second circuit including contacts of each relay closed when the movable member is in its biased 30 35

position for supplying current of the opposite relative polarity to the rails of the section in the rear, an auxiliary contact for each relay included in said second circuit, said auxiliary contact being open when said member is in either extreme position and closed when said member is at rest in its biased position, and means associated with each auxiliary contact for preventing momentary closure thereof during movement of the member from one extreme position to the other. 40 45

9. In combination, a relay having a movable member biased to one position and movable in opposite directions therefrom to two extreme positions, a signal, a proceed indication circuit for said signal including a contact of said relay which is closed when the member is in one extreme position, a caution indication circuit for said signal including a contact of said relay which is closed when the member is in the opposite extreme position, a stop indication circuit for said signal including a contact of said relay which is closed when said member is in its biased position, an auxiliary contact for said relay included in the stop indication circuit for said signal, said auxiliary contact being open when said member is in either extreme position and closed when said member is at rest in its biased position, and means associated with said auxiliary contact for preventing momentary closure thereof during continuous movement of said member from one extreme 50 55 60 65 70 75 position to the other. 80

In testimony whereof I affix my signature.

ROBERT M. GILSON.
